PENNSYLVANIA.

EARTH ANCHOR FOR STRUCTURAL TOWERS.

Application filed December 13, 1924. Serial No. 755,655.

The present invention relates to structural towers of the type used in supporting high tension transmission lines, telegraph or telephone lines, radio antennæ, and for similar purposes, and more particularly to an earth anchor for such towers.

It has heretofore been proposed to support each leg of a tower by means of a stub formed of an angle connected at its lower end to a grillage formed of angles and imbedded in the earth at a considerable distance below the ground level, the legs of the tower being connected to the upper ends of the stubs either slightly below or slightly above the ground level and the stubs being reinforced intermediate their ends to take care of lateral and bending strains.

This method of anchoring towers is objectionable because of the great amount of excavation work required for setting the grillages so far beneath the ground level. Another objection is that with the increase in the size and weight of towers the stubs are subjected to such great bending strains that they are liable to fail in spite of being reinforced to take care of such strains.

By the present invention we provide an anchor construction in which the weight of the tower is supported by a base or grillage imbedded only a short distance below the ground level. A stub extends downwardly from each grillage in a relatively small hole which may be provided by drilling. Each stub has anchor means attached to its lower end and the hole is filled with crushed stone or rubble to a considerable height above such anchor means and the remainder of the hole filled with earth and rammed. Each stub extends a slight distance above its grillage and has a leg of the tower attached to its upper end. Any upward pull on the stubs, due, for instance, to wind pressure on the tower tending to overturn the same, causes the anchor means at the lower ends of the stubs to exert an upward thrust on the crushed rock or rubble in the holes above the anchor means. This crushed rock or rubble presses laterally on the earth walls of the holes and is thereby effective to prevent any upward movement of the stubs. Of course, the packed earth filling the holes above the rock or rubble also assists in resisting the upward pull on the stubs. Thus it will be

seen that the stubs are subjected normally to tension stresses due to upward pull thereon and are relieved substantially of the load due to the weight of the tower. They are therefore subjected to little, if any, bending stresses and consequently need not be reinforced or constructed of particularly heavy angles. The principal advantage of this construction, however, is that it requires a relatively small amount of excavation.

Another feature of the invention is the provision of means in connection with the grillages for protecting the soil beneath them from frost and to a certain extent from rain water or water resulting from melting snow or ice.

The invention is illustrated in the accompanying drawings, wherein:

Figure 1 is a diagrammatic side elevation of a tower having earth anchors embodying our invention;

Figure 2 is a horizontal section along the lines II—II of Figs. 3 and 4;

Figure 3 is a side elevation, partly in section, of the anchor shown in Figure 2;

Figure 4 is a view similar to Figure 3 but taken at right angles thereto;

Figure 5 is a section through the two vertical angle bars of which the stub is comprised;

Figure 6 is a section on the line VI—VI of Figure 3, showing the lower end portion of the stub on a larger scale;

Figure 7 is a detail view on a larger scale of the lower end portion of the stub;

Fig. 8 is a horizontal section along the lines VIII—VIII of Figs. 9 and 10, showing a modified form of anchor.

Figures 9 and 10 are views of such modified form similar to Figures 3 and 4;

Figure 11 is a section through the vertical angle bar which forms the body of the stub of this modified form of anchor;

Figure 12 is a section on the line XII—XII of Figure 9 showing the lower end portion of the stub on a larger scale;

Figure 13 is a detail side view of the lower end portion of the stub on a larger scale, and

Figure 14 is a diagrammatic side elevation of a tower provided with earth anchors of the form shown in Figures 8 to 13 inclusive.

In Figure 1 we have illustrated diagrammatically a structural tower A having legs 2 and diagonals 3. The legs of the tower are connected to earth anchors B which, in accordance with our present invention, will preferably be constructed as hereinafter specifically described.

In the form of the invention illustrated in Figures 2 to 7, inclusive, each earth anchor comprises a laterally extending base or grillage 4 adapted to be imbedded a relatively slight distance below the ground line G—G and a stub 5 extending downwardly from the center of the grillage in a relatively small and deep hole 6 which may be provided by drilling.

The grillage may be formed of a plurality of spaced parallel beams 7 tied together at their ends by angle bars 8. Supported by the beams and extending transversely and centrally thereof are two spaced parallel channel beams 9.

The stub 5 comprises two angle bars 10 arranged with their angles facing away from each other, as shown more particularly in Figure 5. These bars extend between the channel beams 9 and are secured to said channel beams by connecting angles 11 adapted to be riveted or bolted to the legs of the angle bars and to the webs of the channel beams. A leg 2 of the tower is adapted to be secured to the upper end of the stub in any appropriate manner, as by having one of the angle bars 10 extend a slight distance above the adjacent channel beam and riveting the lower end of the leg to such projecting end.

At its lower end the stub has anchor means attached thereto. This anchor means may be of any appropriate construction to provide laterally projecting shoulders for engagement with the crushed rock or rubble 12 which is placed in the hole 6 above the anchor means. As illustrated, however, the anchor means comprises angles 13 which are secured to the legs of the angle bars 10. Reinforcing angles 14 are placed against the legs of the angles 13 and rivets 15 are passed through these reinforcing angles, the legs of the angles 13 and the legs of the angle bars 10, thus securing the parts rigidly together. The angles 13 have horizontal flanges 16 at their upper ends which provide the laterally projecting shoulders referred to.

In order to protect the soil upon which the grillage rests from the action of frost and water, we provide a protecting cover therefor. This cover comprises plates 17 attached at their inner side edges to and supported by angles 18 secured to the webs of the channel beams 9. The plates 17 are supported at their outer side edges and end edges upon a rectangular frame comprising four channel beams 19 connected at the

corners of the frame by angles 20. Plates 21 extend between the channel beams 9 and are supported at their outer ends upon said frame and at their side edges upon angles 22. Two small triangular plates 23 are fitted in the angles between the angle bars 10, thus completing the cover. The channel beams 9 are connected at their outer ends with angles 24 secured to the channel beams 19 of the frame.

The rectangular frame formed by the channel beams 19 and the cover plates 17, 21 and 23 inclose a chamber 25 on the earth bottom of which the grillage rests. In order for the frost to affect the ground immediately below the beams 7 it would have to penetrate to a distance d below the channel beams 19 equal to the horizontal distance s between the beams and the channel beams 19. It will thus be seen that by making the distance s great enough the protecting cover will avoid any likelihood of the ground beneath the beams 7 from being affected by frost. It will also be apparent that this protecting cover provides a substantial water-shed for protecting the ground beneath the beams from rain water or water resulting from melting snow or ice.

In setting the anchor in the ground, the ground will first be excavated to provide a rectangular cavity to place the grillage at the desired distance below the ground line G—G. The hole 6 will next be formed to the desired depth. The stub will then be placed in the hole and the latter filled to the desired height with the crushed rock or rubble 12. After the rock or rubble is rammed the remainder of the hole is filled with dirt which is compacted in the hole. The grillage will then be placed in the cavity and connected to the upper end of the stub. The grillage may be wholly or partly assembled at the place of erection as may be found to be most desirable. After the anchors for a tower have been thus set in the ground and the legs of the tower connected thereto, the cavities above the grillages and their protecting covers will be filled in to the ground line G—G.

The modified form of anchor shown in Figures 8 to 13, inclusive, is designed for lighter tower constructions, such as shown in Figure 14, and does not differ essentially from that already described. The stub B' comprises a single angle bar 26 the legs of which are flattened at the lower end of the angle bar to extend in the same plane. The anchor means secured to the lower end of the stub comprises two angles 27 secured to the flattened portion of the stub on opposite sides thereof. Two other angles 28 are secured to the ends of the angles 27 and extend at right angles thereto.

The grillage of this modified construction comprises I-beams 29 and channel beams 30.

The protecting cover for the grillage comprises a rectangular frame composed of channel beams 31 and cover plates 32 and 33 connected to the channel beams 30 and 31 in an appropriate manner.

When a structural tower is to be provided with earth anchors in accordance with our invention, the grillages will be designed to sustain the load due to the weight of the tower and the stubs will be designed to withstand the tension stresses to which they will be subjected due to upward pull on the stubs caused by forces tending to overturn the tower. The grillages which are embodied in the surface soil which is generally not as compact as the deeper soil, have a considerably greater horizontal area than the anchor means and serve to take the load on the legs and relieve the stubs of downward thrust or bending strains. Since the hole in which the grillage is buried is shallow, it may be easily made much wider than the deep hole in which the stub and anchor means is buried. Of course the forces tending to overturn the tower will be resisted to some extent by the weight of the grillages and their protecting covers. Any upward pull on the stubs will be resisted mainly by the crushed rock or rubble in the holes above the anchor means at the lower ends of the stubs. The upward thrust on this crushed rock or rubble filling will cause the pieces of rock or rubble to be thrust laterally into the earth walls of the holes. The holes must therefore be deep enough so that this lateral thrust of the crushed rock will not cause the earth walls of the holes to give way.

While we have shown and described certain preferred embodiments of our invention, it will be understood that the invention is not limited to the details of construction shown and described but that it may be otherwise embodied within the scope of the appended claims.

We claim:

1. A structural tower having a plurality of spaced legs and earth anchors secured thereto, each anchor comprising a stub extending downwardly in a hole provided therefor and adapted to withstand the tension stresses to which it may be subjected due to the upward pull on the stub caused by forces tending to overturn the tower, said stub having anchor means at its lower end adapted to cooperate with filling material placed above said anchor means to transmit forces due to such upward pull to the surrounding earth and thereby prevent upward movement of the stub, and a laterally extending base at the upper end of the stub for sustaining the portion of the weight of the tower distributed to the leg and adapted

to be secured in place after the anchor means is buried.

2. A structural tower having a plurality of spaced legs and earth anchors secured thereto, each anchor comprising a stub extending downwardly in a hole provided therefor and adapted to withstand the tension stresses to which it may be subjected due to the upward pull on the stub caused by forces tending to overturn the tower, said stub having anchor means at its lower end adapted to cooperate with filling material placed above said anchor means to transmit forces due to such upward pull to the surrounding earth and thereby prevent upward movement of the stub, and a laterally extending base at the upper end of the stub for sustaining the portion of the weight of the tower distributed to the leg and adapted to be secured in place after the anchor means is buried, said base having a considerably greater horizontal area than the anchor means.

3. A structural tower having a plurality of spaced legs and earth anchors secured thereto, each anchor comprising a laterally extending base adapted to sustain the portion of the weight of the tower distributed to the leg, and a stub extending downwardly from said base and adapted to withstand the tension stresses to which it may be subjected due to upward pull on the stub caused by forces tending to overturn the tower, said stub having anchoring means at its lower end adapted to cooperate with filling material placed above said anchor means to transmit forces due to such upward pull to the surrounding earth and thereby prevent upward movement of the stub.

4. A structural tower having a plurality of spaced legs and earth anchors secured thereto, each anchor comprising a laterally extending base adapted to sustain the portion of the weight of the tower distributed to the leg, a stub extending downwardly from said base and adapted to withstand the tension stresses to which it may be subjected due to upward pull on the stub caused by the forces tending to overturn the tower, said stub having anchoring means at its lower end adapted to cooperate with filling material placed above said anchor means to transmit forces due to such upward pull to the surrounding earth and thereby prevent upward movement of the stub, and a protecting cover for said base forming a frost insulating chamber on the bottom of which said base rests.

In testimony whereof we have hereunto set our hands.

EDWARD E. BUECHELE.
SIDNEY A. MARTIN.
